(57) **CLAIM**

The ornamental design for the boat dock fender, as shown and described.

DESCRIPTION

FIG. 1 is a perspective view of the boat dock fender of present invention; and

FIG. 2 is a left side view thereof; and

FIG. 3 is a right side view thereof; and

FIG. 4 is a front plan view thereof; and

FIG. 5 is rear plan view thereof; and

FIG. 6 is a top view thereof; and,

FIG. 7 is a bottom view thereof.

Wherein the dotted lines herein form no part of the claimed design and are illustrated to show use and environment.

1 Claim, 4 Drawing Sheets
